UNITED STATES PATENT OFFICE.

WILLIAM R. HOWARD, OF WASHINGTON, DISTRICT OF COLUMBIA, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR TREATING HYDROCARBONS.

Application filed June 9, 1922, Serial No. 567,034. Renewed March 3, 1927.

This invention relates to improvements in process and apparatus for treating hydrocarbons, and refers more particularly to a process and apparatus for obtaining lower 5 boiling point products from heavy oils by subjecting the latter to the action of heat and pressure.

My invention relates specifically to a process and apparatus for the treatment of oil 10 under heat and pressure wherein the vapors are forced to pass through the heated liquid in a secondary still before passing out through the vapor line, and provides for a process wherein the liquid through which 15 the vapors are forced to pass, may consist of the reflux condensate collected in an inner still in the main distilling apparatus, and one in which this reflux liquid, if desired, may be kept separate from the liquid in the 20 primary distilling apparatus but subjected to the same heat and pressure as the liquid in the primary still, for redistillation.

The single figure in the drawing is a side 25 elevational view of the apparatus showing my invention.

Referring in detail to the drawing, 1 designates the primary still, which may be 30 of the usual horizontal shell type of still shown or, if desirable, a vertical shell still may be used. This still 1 is connected with a set of tubes 2 by the upright legs 3 and 4, forming in effect the well known Heine boiler type. The still may be heated by 35 means of the burner 5 in the fire box 6. Inside the shell 1 is mounted a closed shell 7, of smaller diameter and length to which is 40 attached at the top a vapor line 8. The closed shell 7 may be supported by one or more swinging rods or the rods 7'. Extending from the bottom of the inner shell 7 is a pipe 9, which leads to a point near the 45 top of the shell 1 and above the top of the inner shell 7, terminating as shown at 10. Near the top of the inner shell 7 is a drawoff line 11 for withdrawing the liquid therefrom, having its inlet end submerged in the body of oil in the shell 7 as shown at 31 and its outlet connected to a receptacle or tank (not shown). By manipulating the valves 12 and 13, if desired, the liquid overflowing 50 from the shell 7 may be directed to the main body of oil in the tubes and primary still by closing valve 12 and opening valve 13 which allows circulation by gravity and con-

vection. The liquid level in the shell 7 is 55 above the level A, and through the force of gravity the excess will be reintroduced to the tubes. The convection upward in leg 3 and downward in leg 4 will assist in returning the excess through line 11. When operating 60 normally, the valve 13 is closed and all excess reflux which overflows from the shell 7 is discharged through the valve 12. As higher temperatures are maintained, the liquid in the shell 7 decreases in volume due 65 to the vapors passing over aerial condenser 19. The outer shell 1 is provided with the manhole 14, and at one end of the tubes at the bottom is provided a residuum drawoff line 15 controlled by valve 16. 70

The still 1 is provided with charging line 17 controlled by a valve 18. The vapor line 8 connects to the lower end of a reflux condenser 19, which is provided with the line 20 leading through the water condenser 21 75 and thence connected with the receiver 22. The receiver 22 is provided with pressure relief pipe 23, controlled by valve 24, and liquid drawoff lines 25 and 26 controlled by valves 27 and 28. Liquid level gauge 29 and pressure gauge 30 are also provided on the receiver. 80

The operation of the process is as follows: The outer still 1, tubes 2, legs 3 and 4, are charged to, say, the level indicated by the 85 line A through the charging line 17. The oil is then heated to a distilling temperature by means of the burners 5. As the vapors are formed above the liquid level A, they will gather in the still head or the 90 space above said level, and due to the pressure generated by the expansion and distillation of the liquid, they will be forced into the pipe 9 through the inlet 10, entering the inner shell 7. As these vapors increase, they pass from the inner shell 7 through the vapor line 8 into the aerial condenser and through line 20 and water condenser 21 on into the receiver. The valves 24, 95 27 and 28 being closed in starting the operation, allows a vapor pressure to be generated throughout the entire system. When this pressure has reached the desired operating pressure, valve 24 is used to regulate same.

As the heavier vapors are condensed in the aerial condenser 19, they will fall back through the vapor line 8 and into the inner shell 7, the lighter vapors and incondensable

gases passing on to the receiver. When the liquid level in the inner shell 7 reaches the overflow pipe 11, the overflow will pass out through valve 12 to a tank (not shown) 5 or with valve 12 closed, and valve 13 opened, may be admitted again to the system into the tubes. As further vapors accumulate in the still head, they are forced through pipe 9 and forced to bubble up through 10 the liquid in the inner shell 7, thus cleansing the vapors and allowing the lighter vapors to pass to the aerial condenser 19, forming a better product. The inner shell 7 being in the top of the liquid inside the 15 shell 1 is maintained at a constant high temperature, and it will be seen that the reflux liquid is further cracked and the vapors therefrom forced through the condenser and receiver without the reflux admixing with 20 the contents of the shell 1. This is a desirable feature and does not destroy the viscosity of the oil in the shell 1, which may be drawn off continuously through pipe 15 and used for the purpose of making lubricating oils, which would not be the case if 25 the reflux continually mixed with same.

The following is an illustrative run of my invention: The tubes, legs and still are continuously charged with a California 30 fuel oil of say, 24 gravity Baumé, and heated to a temperature of say, 700-750 degs. F. The apparatus is preferably maintained under an operating pressure of 100 pounds to the square inch. By heating the 35 oil to such temperature under such pressure, a yield of 30-40% of pressure distillate is obtained having a gravity of 48-52 Baumé which on further distillation, will produce 20-25% of commercial gasoline, based on the 40 original charging stock.

I claim as my invention:

1. In an apparatus for converting hydrocarbon oils, the combination with a still adapted to contain a bulk supply of oil, of a 45 closed shell supported therein, a conduit in the vapor space of the still terminating in the body of liquid in the closed shell to cause the vapors released in the still to pass through the oil in the shell, means for withdrawing vapors from the shell connected to a reflux condenser, and for returning the reflux condensate to said shell, liquid drawoff means communicating with the shell and means for maintaining a superatmospheric pressure on the oil and vapors under treatment.

2. In an apparatus for converting oils, the combination with a still in which a body 50 of oil is maintained, and having a vapor space above said body, of a closed shell supported therein, a pipe located in the vapor space of the still communicating with the lower portion of said shell, means for heating the still, drawoff means from the shell 55 connected to a reflux condenser, also con-

stituting the means for returning the condensate to the closed shell for further treatment and a discharge for removing the excess reflux condensate from said shell and means for maintaining a superatmospheric 70 pressure on the oil and vapors under treatment.

3. A process of converting oils, consisting in maintaining a bulk supply in a still and heating same to a vaporizing temperature, 75 causing the vapors to pass through a body of oil maintained in a closed shell within the still, withdrawing the uncondensed vapors from the closed shell, subjecting them to a reflux condensing action, returning the reflux condensate to the closed shell for re-treatment and maintaining a superatmospheric 80 pressure on the oil and vapors under treatment.

4. A process of converting oils, consisting in causing the vapors released from a heated body of oil maintained in a still to pass through a body of reflux condensate maintained in a closed shell within said still, and then subjecting the uncondensed vapors 85 to a reflux condensing action and returning the reflux condensate to the body maintained in the closed shell, maintaining a superatmospheric pressure on the oil and vapors 90 under treatment.

5. A process of converting oils, consisting in causing the vapors released from a heated body of oil maintained in a still to pass through a body of reflux condensate maintained in a closed shell within said still, and then subjecting the uncondensed vapors to a reflux condensing action and returning the reflux condensate to the body maintained in the closed shell, maintaining a superatmospheric pressure on the oil and vapors under treatment, and withdrawing the excess reflux condensate from the closed shell.

6. A process for cracking hydrocarbons comprising maintaining a body of liquid hydrocarbons under cracking conditions of temperature and pressure in an enlarged zone, subjecting vapors evolved from the oil to reflux condensation, maintaining in a second zone a body of reflux condensate in heat interchange relationship with said first body of liquid hydrocarbons, passing oil constituents from said first enlarged zone into said second zone, continuously removing oil constituents from said second zone, subjecting such removed oil constituents to a cracking temperature and subsequently uniting them with said first mentioned body of liquid hydrocarbons.

7. A process for cracking hydrocarbons comprising maintaining a body of liquid hydrocarbons under cracking conditions of temperature and pressure in an enlarged zone, subjecting vapors evolved from the oil to reflux condensation, maintaining in a second zone a body of reflux condensate, in ex-

- ternally heating said second zone, passing vapors evolved from the oil in said first enlarged zone into said second zone, removing liquid oil constituents from said second zone, subjecting the same to a cracking temperature and subsequently introducing them to said first mentioned body of liquid hydrocarbons.
8. An apparatus for cracking hydrocarbons comprising a heating zone, a reaction chamber, means for subjecting vapors evolved from the oil to reflux condensation, an oil receiver adapted to be externally heated by hydrocarbon oil which has passed through said heating zone, means for returning reflux condensate from the reflux condensing means to said oil receiver, means for passing oil constituents from said oil receiver to said heating zone.
9. An apparatus for cracking hydrocarbon oil comprising a heating zone, a reaction zone, dephlegmating means, an oil receiver positioned interiorly in said reaction zone, means for introducing reflux condensate from the dephlegmating means to said oil receiver, means for introducing hydrocarbon constituents from said reaction zone into said oil receiver, means for connecting said oil receiver with said heating zone whereby portions of the oil constituents accumulating in said oil receiver may be passed to said heating zone.

WILLIAM R. HOWARD.
